(21) Appl. No.: **29/262,707**

The ornamental design for an air freshener device, as shown.

(22) Filed: **Jul. 10, 2006**

DESCRIPTION

(51) **LOC (8) Cl.** 23-99

FIG. 1 is perspective view of an air freshener device embodying the present invention;

(52) **U.S. Cl.** D23/366

FIG. 2 is a front view of the air freshener device;

(58) **Field of Classification Search** 392/341,

FIG. 3 is a rear view of the air freshener device;

392/342, 386, 390, 392-394, 401-406; D28/5,

FIG. 4 is a left side view of the air freshener device;

D28/6; 239/34-35, 53-60, 135-136, 326-327,

FIG. 5 is a right side view of the air freshener device;

239/338; D23/355-369; 261/DIG. 17, DIG. 42,

FIG. 6 is a top view of the air freshener device; and,

261/DIG. 65, DIG. 88, DIG. 89; D11/43,

FIG. 7 is a bottom view of the air freshener device.

D11/79
